UNITED STATES PATENT OFFICE.

RICHARD A. ROWLEY, OF DAVENPORT, IOWA.

WRINGER PROTECTOR.

Application filed May 3, 1926. Serial No. 106,477.

This invention relates to accessories for or attachment to clothes wringers and has for its object the provision of a novel guard device adapted to be mounted adjacent and in connection with the relatively stationary and relatively bodily movable rollers of a clothes wringer for the purpose of preventing clothes from sticking to the rollers and being carried thereabout and consequently wrapped about the rollers.

An important object is the provision of a guard device embodying a stationary member adapted to be secured to the frame adjacent the relatively stationary or lower roller, and a guard device adapted to be pivoted upon the frame and operatively engaged by the shaft or spindle of the relatively bodily movable roller whereby to accommodate itself always to the position thereof and to cooperate with the stationarily mounted guard for the purpose of preventing clothes from being carried about the rollers and becoming clogged or tangled.

An additional object is to provide a device of this character which will be simple and inexpensive to manufacture, easy to use, positive in action, efficient and durable in service, and a general improvement in the art.

With the above and other objects and advantages in view, the invention consists in the novel construction and arrangement of elements to be hereinafter more fully described and claimed, and illustrated in the accompanying drawings, in which:—

Figure 1 is a perspective view of a clothes wringer equipped with the device.

Figure 2 is a detail perspective view partly broken away and in section and partly in diagram illustrating the mounting of one of the guards, and

Figure 3 is a similar view showing the mounting of the other guard.

Referring more particularly to the drawing, the letter A designates the frame of a wringer of any ordinary or preferred type and which may be provided with any suitable means, not shown, whereby it may be attached to a wash tub, stationary washstand or other support. As is customary, the wringer frame A carries rollers B and C journaled therein connected for simultaneous movement as by means of gears D and E at both ends thereof arranged in interfitting relation. The shaft or spindle of one roller is extended as shown at F and carries a

crank handle G whereby rotation of both of the rollers may be effected for wringing out clothes. Ordinarily, devices of this character are provided with adjusting means, indicated at H, whereby the tension of the upper roller B with respect to the lower one C may be regulated.

In carrying out the invention, I provide a guard device indicated generally by the numeral 10, for the lower roller and a somewhat different guard device, indicated generally by the numeral 11, for the upper roller. The guard device 10 may consist simply of an elongated plate or strip of metal provided at its ends with laterally extending ears 12 apertured as shown at 13 for the passage of suitable securing screws, nails or the like whereby it is attached to the inner sides of the upright members which constitute the sides of the frame A. It is intended that this guard member 10 be so located that the upper edge thereof will be adjacent the point or line at which the rollers B and C contact.

The guard member 11 may likewise be formed as an elongated strip 14 of metal provided at its ends with lateral extensions 15 of greater height which are notched or cut away at their central portions, as indicated at 16 for the reception of the spindle or shaft of the upper roller B. The notching or recessing 16 defines upper and lower arms 17 and 18, the former of which is longer than the latter and apertured as indicated at 19 for the passage of a suitable screw or the like whereby the guard member 11 may be properly mounted on the inside of the upright members constituting the frame A. It will be observed that the employment of a single securing screw or the like passing through the aperture 19 at each end of the device provides a pivotal connection so that the upper roller may be adjusted by means of the adjusting devices indicated at H or any equivalent structure, the guard member 11 always remaining in the same relation to the upper roller B so that the coaction of the guards 10 and 11 will be unimpaired.

When the parts are properly installed or positioned as indicated in Figure 1 of the drawings, it will be quite clear that the guard members 10 and 11 will be so arranged that when clothes are fed to the wringer they cannot possibly follow the roller around and consequently become bunched up and probably injured as the result thereof. Ob-

viously, it becomes necessary at times to adjust the upper roller B with respect to the lower roller C, depending upon the thickness or nature of the fabric being wrung out 5 and it is for this reason that the pivotal mounting for the guard member 11 is provided. It is really thought that the construction, operation and advantages will be 10 readily apparent to one skilled in the art without further explanation.

While I have shown and described the preferred embodiment of the invention, it should be understood that I reserve the right to make such changes in the form, construction 15 and arrangement of parts as will not depart from the spirit of the invention or the scope of the subjoined claim.

Having thus described the invention, I claim:—

20 A stripper attachment for a clothes

wringer including spaced upright side members and a pair of coacting rolls journaled therebetween one of which is movable with respect to the other, comprising a substantially U-shaped metallic member including 25 an upstanding plate portion adapted to be located immediately adjacent the movable roll and the legs of the U terminating in lugs recessed at their central portions for the accommodation of the roll trunnions or axle, 20 the lugs being provided with means so as to be pivotally connected upon the confronting faces of said upright sides whereby said metallic member may accommodate itself to adjustment of the movable roll with respect to 25 the other roll.

In testimony whereof I affix my signature.

RICHARD A. ROWLEY.
